UNITED STATES PATENT OFFICE.

ARTHUR I. RISSE, OF CHICAGO, ILLINOIS, ASSIGNOR TO U. S. BOTTLERS MACHINERY CO., OF CHICAGO, ILLINOIS, A CORPORATION OF ILLINOIS.

BOTTLE-WASHING MACHINE.

Application filed July 20, 1922. Serial No. 576,196.

To all whom it may concern:

Be it known that I, ARTHUR I. RISSE, a citizen of the United States, residing at Chicago, in the county of Cook and State of Illinois, have invented a certain new and useful Improvement in Bottle-Washing Machines, of which the following is a specification.

This invention relates to bottle washing machines, particularly that class of such machines in which a large quantity of bottles are fed into the machine, carried through it, there washed inside and out and finally carried away from the machine to a predetermined desired point.

The object of the invention is to provide a machine of this class which can be more easily and cheaply constructed than devices heretofore in use, which is very satisfactory and efficient in operation, and which is not liable to get out of order.

The invention consists in means for attaining the foregoing objects, comprising among others:

25 A device for carrying bottles in inverted position through the washing mechanism and then safely reversing their position as they are placed upon a conveyor which takes them away from the machine; in specific 30 means for positively and accurately feeding the bottles in a step by step motion to the washing mechanism, and for positioning them in that mechanism; in means for safely landing a bottle being turned from inverted to upright position upon a carrier mechanism adapted to convey it away from the machine; in mechanism for rendering the latter mechanism safe so that it does not crush bottles being delivered to it, even 35 should there be an obstruction to its operation which would, under other conditions, cause a bottle being operated upon to be crushed; means for adjusting the machine so as to handle bottles of different sizes without changing the principal mechanism of the device; a carrier belt for transporting bottles through the washing mechanisms, which insures each successive group of bottles carried by it being in the same horizontal position as they pass under the washing devices; a novel feeding mechanism for moving such groups of bottles one after the

other into a definite pre-determined position under the washing mechanism.

The invention further consists in many details and features of construction which will be hereafter more fully set forth in the specification and claims.

Referring to the drawings in which like numerals designate the same parts throughout the several views:

Figure 1 is a side view of a complete machine illustrating this invention in its preferred form, certain parts being shown in section.

Figure 2 is a plan view of the machine of Figure 1, the drier and washer hoods being removed so as to show the mechanism within them—some parts being also shown partly in section.

Figure 3 is a sectional end view on the line 3—3 of Figure 1.

Figure 4 is a sectional detail view on the line 4—4 of Figure 2, and Figure 5 is a sectional detail view on the line 5—5 of Figure 4, these two views showing details of the mounting of the conveyor which carries the bottles through the washing devices.

Figure 6 is an enlarged plan view of one-half of the conveyor, showing the operating pawl and stop for giving the conveyor its step by step motion—in changed position view from that of Figure 2.

Figure 7 is a side view of the mechanism of Figure 6 taken on the line 7—7 of that figure.

Figure 8 is a detail view, partly in section, on the line 8—8 of Figure 2, certain parts being removed and the parts shown being in changed position from that of Figure 2.

Figure 9 is a sectional detail view on the line 9—9 of Figure 2.

Figure 10 is a perspective view of part of the bottle slide and guard.

Figure 11 is a perspective view of the bottle engaging bumper broken away in the center on account of lack of space for full illustration.

Figures 12 and 13 are perspectives of the ends and roller supports of bottle carrying cleats entering into the construction of the conveyor.

The machine of the drawings illustrating

this invention is supported from the floor 18 by a frame-work, including a plurality of upright standards 20, 21, 22, 23, 24 and 25 connected together longitudinally of the machine 5 by a plurality of suitably arranged horizontal members 26, 27, 28, 29 and 30, and suitably cross-connected as is necessary by horizontal members, such as 32, 33, 34 and 35. Suitably journaled at the right-hand or front 10 end of the machine, as shown in Figures 1 and 2, are two transverse shafts, 36 and 38, each carrying at its opposite ends a sprocket wheel 40, adapted to receive and drive the links 42 of parallel sprocket chains, arranged as shown in the drawings, with the main or extended portions of the chains in horizontal position, within a tunnel-like cover 44, rising from the upper longitudinal frame members or table top 46, carried by 15 supports 24 and 25.

Each alternate link 42 of these sprocket chains is provided with a horizontally extending bracket 48 in alignment or register with the corresponding bracket on a link on 20 the opposite sprocket chain so that the two chains may be connected together at alternate links by means of bottle carrying bars 50, preferably channel shaped, each detachably secured in place by a bolt 52 passing 25 through the end of the bar 50 and the adjacent bracket 48, and entering a little truck frame 54. These frames are provided with suitable anti-friction devices—such, for instance, as rollers 56, adapted to travel on 30 suitable horizontal track rails 60, rigidly supported, between the sprocket wheels by any suitable means—as, for instance, uprights 62, carried by horizontal cross-frame members, such as 33.

Each bar 50 is provided along its length 35 with a plurality of spaced perforations 64, entering outwardly flaring conical bottle receiving cups 66, preferably but not necessarily made as shown in the drawing, integral with the bars themselves, and of such a size and shape that the necks 68 of bottles 70 to be washed will, as shown in the drawing, fit within the cups and practically close perforations 64 so that cleaning liquid, usually 40 water, delivered by one set of nozzles 72, or compressed air delivered by another set of nozzles 74 to a given set of perforations 64, having bottles above them, must pass up 45 into the bottles and cannot go anywhere else.

In the particular machine here illustrated, 50 a set of these nozzles 72 is mounted at proper intervals along a cleaning liquid, usually water, supply pipe 76, extending transversely of the machine and of the path of travel of the bar carrying sprocket chains, and a corresponding set of the air nozzles 74 is mounted in a similar compressed air pipe 78, parallel to pipe 76 and spaced just a sufficient 55 distance therefrom so that when a given bottle carrying bar is moved one step, to be

hereafter described, through the machine, it will travel from exact register with one set of nozzles 72 to the adjacent set of air nozzles 74. So far as the principles of the machine are concerned, cleaning liquid, usually water under pressure, may be supplied to pipe 76 from any suitable source of supply and compressed air may be correspondingly supplied to pipe 78.

In the particular case illustrated in Figure 3, cleaning liquid under pressure may be supplied to pipe 76 via pipes 80 and 82 from an external supply pipe 84, controlled by a valve 86; or, it may be furnished by a rotary pump 88 operating through an open control valve 90 to draw liquid via pipes 92 and 94 from a drainage tank 96—located at the bottom of the machine and adapted to receive the cleaning liquid which passes into it from the bottles 70, after it has been forced into the bottles from nozzles 72. Under the last conditions, a valve 98 below the tank must be kept closed, instead of being open to the sewer or the like, as it must be when the source of supply is direct from pipe 84. Re-pumping of cleaning liquid from tank 96 will only take place when a cleaning liquid—as, for instance, a chemical one of considerable value is used and it is therefore desirable to obtain full value from the chemicals. When plain water under pressure is used, the usual practice will be to open valve 86, close valve 90, open valve 98 and let the water flow freely, pump 88 being under these conditions at rest.

As the machine is intended to include, when desired, exterior cleansing of the bottles as well as interior cleansing, the pipe 82—heretofore referred to—is extended up to a horizontal pipe 100 extending through the cover 44 and over the row of bottles 70, which happen to be in register with nozzles 72. In pipe 100, immediately over the row of bottles 70, are a plurality of discharge nozzle perforations 102, preferably but not necessarily enclosed with a guiding hood 104, so arranged that cleaning liquid delivered from these nozzles will, as shown in Figures 3 and 9, forcibly strike and wash the exterior surfaces of the row of bottles which are being washed internally by the sprays of liquid from the respective nozzles 72. The nozzles 102 receive the same kind of cleaning liquid under pressure, viz, direct water pressure, or liquid return from tank 96, as is passing through nozzles 72 into the bottles.

In order to blow compressed air into the bottles expeditiously, it is necessary to provide accurate means for first registering a given group of bottles on a suitable set of nozzles 72 and then moving them into accurate register with the corresponding set of air nozzles 74. In order to insure such movement of the bottle carrying bars 50, a special positive acting step-by-step motion

device has been invented which will now be described.

The mechanisms referred to are in duplicate, one at each side of the machine operating on adjacent ends of bars 50. As they are, except for position, alike, only one will be described.

Horizontally reciprocatable longitudinally of the machine, adjacent to the ends of the bars 50 in suitable supports 106 and 108, is a horizontal shaft 110, having pivoted to it, at its left-hand end, as shown in the drawings, a connecting rod 112, driven through an eccentric band 114 by an eccentric 116, carried by a transverse shaft 118, extending across the machine and suitably journaled by conventional means, this shaft being constantly driven by any suitable means, as for instance, gear 120, worm 122, belt 124, an electric motor 126 receiving electricity in conventional manner from a source not shown.

Connecting rod 112 is provided intermediate of its length with a conventional form of yielding mechanism, specifically a spring 128, interposed between a block 130 on the end of rod 112, proper, and a cross-head 132, carried by parallel rods 134 from eccentric band 114, the result being as well understood in the connecting rod art, that the rotation of eccentric 116 drives connecting rod 112 and attached parts to reciprocate rod 110; but that, if an obstruction is encountered by rod 110, spring 128 will permit the reciprocation of cross-head 132 along rod 112 against the action of spring 128, thereby preventing injury to rod 110 and attached parts.

Rising from fixed support 106 is a stationary vertical pivot 136 on which a lever arm 128 is laterally rockable. Rod 110, which reciprocates through the bottom of this support 106 and through the axial line of this pivot 136, has rigidly attached to it beyond this pivot, to the right as shown in the figures, a fixed cross-head 140, carrying a vertical pivot 142 on which another horizontally rockable arm 144 is journaled.

The outer or free swinging end of arm 138 is provided with an enlargement which loosely encloses arm 144 so that the latter arm can slip through the enclosing means on the end of arm 138. In the particular case here illustrated, this enclosing means consists simply of two pins 146, joined by a link 148 which passes over the arm 144 and fits loosely enough thereon so that the arm 144 can slide freely beneath the link 148 and between the pins 146.

Arm 144 is provided at its outer free swinging end with a hook 150, adapted in the position shown in Figure 6, to engage the upwardly extending free end of an adjacent bolt 52 at the end of the bottle carrying bar and clamp it against an adjacent end

154 of arm 138 to thereby in the position of Figure 6 positively lock that particular bar 50 in predetermined horizontal position along the track 60 which predetermined position is one in which bottles carried by that particular bar 50 register with the nozzles 72 below it.

The outer free swinging end of arm 144 is also provided with an angular cam face 156 adapted to engage and operate upon successive bolt ends 52. In Figure 6, the forward tip end of the cam is shown engaging a particular bolt end 52^a. In this particular case, movement of rod 110 to the right (as viewed in Figure 6) carries the arm 144 to the right from the position of Figure 6 toward that of Figure 2, and the engagement of cam face 156 with bolt end 52^a forcibly moves arm 144 and consequently arm 138 downward, as viewed in Figure 6, to release the particular bolt 52, engaged by hook 150 in Figure 6, and move arm 138 out of its path of travel when it subsequently begins to move to the left. At the end of this movement of shaft 110 to the right, hook 150 engages bolt 52^a, and as shaft 110 begins to move to the left, it pulls bolt 52^a and its bottle carrying bar 50 to the left—unobstructed by arm 138. Bolt 52^a, and its particular bar 50, can therefore by a single rotation of shaft 118 be moved by the mechanism described from its position in Figure 6 to that of the bar and bolt shown at 52 in that figure.

Spring 158 normally urges arm 148 and consequently arm 138 into the path of longitudinal travel of the bolts 52, thereby insuring engagement of hook 150 with a bolt 52 whenever the position of the cam 156 will permit it.

In the operation of the mechanism thus far described, shaft 118 and eccentric 116 rotate continuously to reciprocate rod 110 to thereby in the manner described cause the arms 138 and 144 to engage successive bolt ends 52 and thereby move the bottle carrying bars 50 in a step by step motion to the left, as viewed in Figures 1 and 2, first between nozzles 72 and 102 and then over nozzle 74.

The bottles are supplied to the machine by an operator who stands at the front end and, from a suitable source of supply, loads each bar as it comes up to the top of the adjacent sprocket wheels 40 by placing a bottle in each of the bottle receiving cups 66 carried by that particular bar. As the bottles move to the left, through the machine beyond nozzles 74, any cleaning liquid within them, which has not been driven out by the compressed air delivered by nozzles 74, drains out of them through perforation 64 into the tank 96. After leaving the nozzles 74, the bottles are carried in a successive step by step motion to the left until, as the chains pass over left-hand sprocket wheels 40 of

Figure 1, they reach approximately the dotted line bottle position of that figure where they are free to fall by gravity through the path indicated by successive 5 positions in Figure 8 onto the delivery conveyor mechanism 160 which carries them through a drying room or compartment 162 where they are heated by any suitable means as for instance, coils 164, before being 10 finally manually removed from the machine. The particular conveyor mechanism 160 may be of any conventional form driven by any suitable means and its details are therefore not shown in the drawing, except one pulley 15 166 which conventionally supports it.

The washing and draining operations heretofore described require that the bottles be carried as shown in inverted position, viz: With the bottle necks downward; and, 20 similarly, it is desirable—if not absolutely necessary—that the bottles be right-side up in passing through drying chamber 162, and the bottles cannot be allowed to fall freely from the washing conveyor mechanism to 25 the drying conveyor mechanism: first, because there would be great danger of breaking bottles; second, because they would not position themselves in any suitable manner on the drying conveyor. Means are therefore provided for especially guiding and 30 controlling the bottles as they fall from the washing to the drying conveyor. For this purpose, a plurality of inclined chutes 168 are provided—one in the path of each bottle 35 which is to be delivered from the bottle washing mechanism. In the particular case here illustrated, they are rigidly secured to cross-bars 170 on the frame of the machine, preferably but not necessarily made adjustable with reference to the side frames of 40 the machine, through pin and slot connections 172, so that they may be selectively positioned below the left-hand or delivery end of the bottle washing conveyor mechanism. To insure the passage of bottles down 45 these chutes 168, guard plates 174 are suitably secured at opposite ends of the row of parallel chutes 168. Any suitable means may be used for securing these 50 devices in position. The chutes 168 and the guard plates 174 form three sides of a passage down which the bottles move from the washing conveyor mechanism to the drying conveyor and, for safe handling of the bottles, it is necessary to provide a fourth side 55 which will retain and protect the bottles, as they fall through the successive positions of Figure 8 to the conveyor 160 and then get 60 out of the way of the bottles, so that they can be carried by the conveyor to the drying compartment. In the particular case here illustrated, this fourth side of the guiding passageway is an upright board or bumper 65 176, preferably faced with rubber 178 where it engages the bottles, provided with suit-

able guide cleats 180 for individual bottles, terminating at their upper ends in an angularly disposed horizontal guide flange 182, extending above the bumper proper. This bumper is sustained at its lower end by a 70 pair of parallel rods 184 pivoted thereto, the opposite ends of said rods being pivoted at 186 on frame members 26. The bumper 176 is supported at its upper edge by similar parallel rods 188 of less length than rods 184, said rods being rigidly connected at their opposite ends to a shaft 190, journaled in suitable bearing blocks 192 on up-right frame members 21. Rigid with shaft 190 is an arm 194 carrying an adjustably positioned counter-weight 196, adapted to counter balance rods 184, 188, and bumper 176, so that these latter parts may be readily moved between dotted and full line positions of Figure 8 as shaft 190 rocks as here- 80 after described.

Shaft 190 also carries rigid with it a broken lever of conventional form, comprising a short lever arm 198, rigid with the shaft, the same having an angular flange 200 which overlaps and bears against a second or supplemental lever 202 pivoted to the first lever at 204 so that, assuming lever 198 is rigid, lever 202 can swing in a clock-wise direction, as viewed in Figure 8, away from flange 200; but is prevented by said flange from swinging in the opposite direction about the pivot with reference to the first lever. Suitably attached to supplemental lever 202 at a convenient point, as 206, is one end of a retractile spring 208 whose opposite end is attached—as for instance—means of bracket 210 to a stationary point on the machine. These parts just described are so arranged and disposed that this spring will normally hold the bumper 176 and connecting rods 188—184 in their elevated or dotted line position of Figure 8.

Lever 202 is so positioned with reference to shaft 118 that it extends into the path of travel of a cam arm 214, carrying a cam wheel 216 adapted to engage the arm and thus at a predetermined point in the rotation of shaft 118 swing lever mechanism 198—202, and consequently the bumper mechanism mounted moving in unison therewith, from the dotted line to the full line position of Figure 8. This cam mechanism 214—216 is so timed with other parts of the machine controlled by shaft 118, as heretofore described, that the bumper 176 will be in the full line position of Figure 8 just at the instant when a given bottle carrying bar 50 has reached the proper angular position so that it is ready to have the bottles carried by it fall off and pass down the chutes 168 to the carrier 160. This cam mechanism is also proportioned so that the bumper only remains in this full line position long enough to steady the falling bot- 12 13

ties into proper place in the chutes 168, whereupon it begins to move upward to the dotted line position of Figure 8, thus leaving the bottles on the carrier 160 to be transported into the drying chamber.

The bumper 176 does not move any bottle vertically but when a bottle is out of position, as shown in dotted lines, Fig. 8, the bumper in moving from dotted to full line position of that figure shoves the bottle over against chute 168 thus straightening the bottle up while falling in the chute.

The rods 184 are purposely differentiated in length from the rods 188 so as to insure rapid movement of the lower edge of the bumper away from the bottles on the carrier 160 as the bumper moves upward to the position where it entirely clears them so that the bottles can be carried under it by the conveyor 160.

By using the straight bumper 176 extending across the conveyor 160 and by providing this described movement for the bumper, the bottles 70 are steadied and protected as they fall from the washing mechanism to the conveyor and are arranged in straight lines across the conveyor, as is shown in the left-hand portion of Figure 2, thus leaving them in good position for ready removal from this conveyor by operator stationed at the left-hand end of the machine, as viewed in Figures 1 and 2.

The lever 198—200 is made in the form of a broken lever so that if in case of accident, bumper 176 in descending from the dotted line to the full line position of Figure 8 strikes an obstruction—as, for instance, a misplaced bottle on conveyor 160, and would thereby be unable to move further without damage, the lever 202 can still be moved on pivot 204 by cam mechanism 114—116 to and through the full line position of Figure 8 and back again into contact with flange 200.

In the complete operation of the machine, the motor 126 is started, power from any suitable source (not shown) is applied to conveyor 160, cleaning liquid is admitted from one source or the other to pipe 82 and compressed air is admitted from any suitable source to pipe 78. Thereupon, the operator standing in front of the machine places a row of bottles to be cleaned on the nearest horizontally disposed bottle carrying bar 50 and upon each succeeding bar as it reaches that position. The operation of the machine causes these loaded bars to move in a step by step motion, first to the liquid discharge nozzles 72 and 102, then to the air discharge nozzles 74, and finally to the top of the chutes 168, down which the bottles are discharged to the conveyor 160, they being in this movement steadied and guided by the bumper mechanism 176 which, after performing its function, moves up to the dotted line position of Figure 8

and allows the bottles to pass, first, to the drying chamber 162; and finally to the hands of operators who remove the clean bottles from the machine.

The bars 50 are each provided on one side with a horizontally extending flange 218, reaching sufficiently close to the next adjacent bar to aid in spacing the bars apart as they travel, loaded with bottles, along the tracks 60.

What I claim is:

1. In mechanism of the class described, a normally horizontally disposed bottle conveyer, there being a perforation in the conveyer, an inverted conical cup on the conveyer adapted to receive the neck of an inverted bottle and hold it in register with said perforation, means moving the conveyer from the horizontal to an inclined position where a bottle will fall out of said cup off the conveyer, and automatic means including a stationary inclined chute and means urging a bottle against the chute guiding a bottle, to fall, to upright position.

2. In mechanism of the class described, a normally horizontally disposed bottle conveyer, there being a perforation in the conveyer, an inverted conical cup on the conveyer adapted to receive the neck of an inverted bottle and hold it in register with said perforation, means moving the conveyer from the horizontal to an inclined position where a bottle will fall out of said cup off the conveyer, automatic means including a downwardly inclined chute, and means directing a falling bottle against the chute guiding a bottle, so falling, to upright position, a laterally moving conveyer for receiving the upright bottle and means moving the guiding means out of the way of a bottle which it has guided to said conveyer.

3. In mechanism of the class described, in combination, a laterally moving conveyer, a chute periodically dropping bottles on said conveyer, a bumper, and means moving the bumper between two positions in one of which it guides a bottle to upright position on the conveyer and in the other of which it clears the bottle as the conveyer carries it.

4. In mechanism of the class described, in combination, a laterally moving conveyer, a chute periodically dropping bottles on said conveyer, a bumper, and means moving the bumper between two positions, one above the conveyer where it clears a bottle carried by it, the other adjacent to the conveyer to contact and guide a falling bottle into position on it.

5. In mechanism of the class described, in combination, a laterally moving conveyer, a chute periodically dropping bottles on said conveyer, a bumper, means moving the bumper between two positions, one above the conveyer where it clears a bottle carried

by it, the other adjacent to the conveyer to contact and guide a falling bottle into position on it, and means operating to move the bottom of the bumper at a different speed than its top—out of the way of the bottle on the conveyer.

6. In mechanism of the class described, in combination with a chute a generally vertical bumper facing the chute, a pair of generally horizontal pivoted rods supporting the bottom of the bumper, a pair of substantially shorter pivoted rods supporting the top of the bumper, and means rocking one of said sets of rods to normally elevate the bumper.

7. In mechanism of the class described, in combination with a chute a generally vertical bumper facing the chute, a pair of generally horizontal pivoted rods supporting the bottom of the bumper, a pair of substantially shorter pivoted rods supporting the top of the bumper, means rocking one of said sets of rods to normally elevate the bumper, and power means equipped with a safety yieldable device for forcing the bumper downward.

8. In mechanism of the class described, a conveyer to be moved step by step, two spaced members along the conveyer, an arm pivoted to a fixed point beside the path of travel of the conveyer with a part which can move into the path of the first of said spaced members on the conveyer to temporarily prevent movement of the conveyer, a member reciprocable beside the conveyer adjacent to said first swinging arm, a second arm pivoted on and carried by the reciprocable member having on its swinging end a hook for successively engaging the spaced members on the conveyer, means loosely connecting the two arms so the second reciprocates with reference to the first as they both swing about their pivotal points, a cam on the second swinging arm engaging the second spaced member on the conveyer so shaped that as the reciprocable member moves the second swinging arm past said second spaced member, the first swinging arm is moved laterally of the conveyer clear of the path of travel of the first spaced member thereon.

9. In mechanism of the class described, a conveyer to be moved step by step, two spaced members along the conveyer, an arm pivoted to a fixed point beside the path of travel of the conveyer with a part which can move into the path of the first of said spaced members on the conveyer to temporarily prevent movement of the conveyer, a member reciprocable beside the conveyer adjacent to said first swinging arm, a second arm pivoted on and carried by the reciprocable member having on its swinging end a hook for successively engaging the spaced members on the conveyer, means

loosely connecting the two arms so the second reciprocates with reference to the first as they both swing about their pivotal points, a cam on the second swinging arm engaging the second spaced member on the conveyer so shaped that as the reciprocable member moves the second swinging arm past said second spaced member, the first swinging arm is moved laterally of the conveyer clear of the path of travel of the first spaced member thereon, and means urging the swinging arms to engage the spaced members on the conveyer.

10. In mechanism of the class described, a conveyer to be moved step by step, two spaced members along the conveyer, an arm pivoted to a fixed point beside the path of travel of the conveyer with a part which can move into the path of the first of said spaced members on the conveyer to temporarily prevent movement of the conveyer, a member reciprocable beside the conveyer adjacent to said first swinging arm, a second arm pivoted on and carried by the reciprocable member having on its swinging end a hook for successively engaging the spaced members on the conveyer, means loosely connecting the two arms so the second reciprocates with reference to the first as they both swing about their pivotal points, a cam on the second swinging arm engaging the second spaced member on the conveyer so shaped that as the reciprocable member moves the second swinging arm past said second spaced member, the first swinging arm is moved laterally of the conveyer clear of the path of travel of the first spaced member thereon, and a spring between the reciprocable member and the second arm normally urging it toward the spaced members on the conveyer.

11. In mechanism of the class described, a conveyer to be moved step by step, two spaced members along the conveyer, an arm pivoted to a fixed point beside the path of travel of the conveyer with a part which can move into the path of the first of said spaced members on the conveyer to temporarily prevent movement of the conveyer, a member reciprocable beside the conveyer adjacent to said first swinging arm, a second arm pivoted on and carried by the reciprocable member having on its swinging end a hook for successively engaging the spaced members on the conveyer, means loosely connecting the two arms so the second reciprocates with reference to the first as they both swing about their pivotal points, a cam on the second swinging arm engaging the second spaced member on the conveyer so shaped that as the reciprocable member moves the second swinging arm past said second spaced member, the first swinging arm is moved laterally of the conveyer clear of the path of travel of the first spaced

member thereon, and power means continuously reciprocating the reciprocable member.

12. In mechanism of the class described, a conveyer to be moved step by step, two spaced members along the conveyer, an arm pivoted to a fixed point beside the path of travel of the conveyer with a part which can move into the path of the first of said spaced members on the conveyer to temporarily prevent movement of the conveyer, a member reciprocable beside the conveyer adjacent to said first swinging arm, a second arm pivoted on and carried by the reciprocable member having on its swinging end a hook for successively engaging the spaced members on the conveyer, means loosely connecting the two arms so the second reciprocates with reference to the first as they both swing about their pivotal points, a cam on the second swinging arm engaging the second spaced member on the conveyer so shaped that as the reciprocable member moves the second swinging arm past said second spaced member, the first swinging arm is moved laterally of the conveyer clear of the path of travel of the first spaced member thereon, power means continuously reciprocating the reciprocable member, and yielding mechanism between the power means and the reciprocable member for the purposes set forth.
13. In mechanism of the class described, a conveyer to be moved step by step, two spaced members along the conveyer, an arm pivoted to a fixed point beside the path of travel of the conveyer with a part which can move into the path of the first of said spaced members on the conveyer to temporarily prevent movement of the conveyer, a member reciprocable beside the conveyer adjacent to said first swinging arm, a second arm pivoted on and carried by the reciprocable member having on its swinging end a hook for successively engaging the spaced members on the conveyer, means loosely connecting the two arms so the second reciprocates with reference to the first as they both swing about their pivotal points, a cam on the second swinging arm engaging the second spaced member on the conveyer so shaped that as the reciprocable member moves the second swinging arm past said second spaced member, the first swinging arm is moved laterally of the conveyer clear of the path of travel of the first spaced member thereon, power means continuously reciprocating the reciprocable member, and yielding mechanism between the power means and the reciprocable member for the purposes set forth.
14. In mechanism of the class described, a conveyer to be moved step by step, two spaced members along the conveyer, an arm pivoted to a fixed point beside the path of travel of the conveyer with a part which

can move into the path of the first of said spaced members on the conveyer to temporarily prevent movement of the conveyer, a member reciprocable beside the conveyer adjacent to said first swinging arm, a second arm pivoted on and carried by the reciprocable member having on its swinging end a hook for successively engaging the spaced members on the conveyer, means loosely connecting the two arms so the second reciprocates with reference to the first as they both swing about their pivotal points, a cam on the second swinging arm engaging the second spaced member on the conveyer so shaped that as the reciprocable member moves the second swinging arm past said second spaced member, the first swinging arm is moved laterally of the conveyer clear of the path of travel of the first spaced member thereon, power means continuously reciprocating the reciprocable member, and yielding mechanism between the power means and the reciprocable member for the purposes set forth.

15. In mechanism of the class described, a conveyer to be moved step by step, two spaced members along the conveyer, an arm pivoted to a fixed point beside the path of travel of the conveyer with a part which can move into the path of the first of said spaced members on the conveyer to temporarily prevent movement of the conveyer, a member reciprocable beside the conveyer adjacent to said first swinging arm, a second arm pivoted on and carried by the reciprocable member having on its swinging end a hook for successively engaging the spaced members on the conveyer, means loosely connecting the two arms so the second reciprocates with reference to the first as they both swing about their pivotal points, a cam on the second swinging arm engaging the second spaced member on the conveyer so shaped that as the reciprocable member moves the second swinging arm past said second spaced member, the first swinging arm is moved laterally of the conveyer clear of the path of travel of the first spaced member thereon, power means continuously reciprocating the reciprocable member, and yielding mechanism between the power means and the reciprocable member for the purposes set forth.

16. In mechanism of the class described, a conveyer to be moved step by step, two spaced members along the conveyer, an arm pivoted to a fixed point beside the path of travel of the conveyer with a part which can move into the path of the first of said spaced members on the conveyer to temporarily prevent movement of the conveyer, a member reciprocable beside the conveyer adjacent to said first swinging arm, a second arm pivoted on and carried by the reciprocable

- member having on its swinging end a hook for successively engaging the spaced members on the conveyer, means loosely connecting the two arms so the second reciprocates 5 with reference to the first as they both swing about their pivotal points, a cam on the second swinging arm engaging the second spaced member on the conveyer so shaped that as the reciprocable member moves the 10 second swinging arm past said second spaced member, the first swinging arm is moved laterally of the conveyer clear of the path of travel of the first spaced member thereon, a spring between the reciprocable member 15 and the second arm normally urging it toward the spaced members on the conveyer, power means continuously reciprocating the reciprocable member, and yielding mechanism between the power means and the reciprocable member for the purposes set forth.
17. In mechanism of the class described, in combination with a series of members 52 to be moved an arm 138 pivoted at one end to a fixed point having at its other end an abutment 154 adapted to engage an adjacent one of said members 52, a reciprocating shaft 110 adjacent thereto, a second arm 144 pivoted to the shaft having at its free end a hook 152 adapted to selectively engage one of said 25 members 52, to be moved, a sliding connection between the ends of the two arms, a spring urging the arms to the side of the shaft and a cam on the end of the second swinging arm resisting said spring by engaging one of said 30 members 52, all the parts being arranged and disposed as shown and described for the purposes set forth.
18. In mechanism of the class described, a horizontally disposed conveyer carrying bottles in inverted position, another lower horizontally disposed conveyer and means com-
- prising an inclined chute and a reciprocable bumper facing the conveyer guiding bottles safely from the former conveyer to upright position on the second conveyer for the purposes set forth. 45
19. In mechanism of the class described, a conveyer to be moved step by step, projecting members on opposite sides thereof, a hooked swinging reciprocatable member 50 adjacent to each projecting member, means reciprocating said swinging members to pull the conveyer a given distance and means actuated by the swinging members moving into the paths of the projecting members 55 as they finish their movements to positively stop them and the conveyer.
20. In mechanism of the class described, a conveyer to be moved step by step, projecting members on opposite sides thereof, a hooked swinging reciprocatable member 60 adjacent to each projecting member, means reciprocating said swinging members to pull the conveyer a given distance and rockable arms actuated by the swinging members moving into the paths of the projecting members 65 as they finish their movements to positively stop them and the conveyer.
21. In mechanism of the class described, a conveyer for bottles being washed; another conveyer for bottles leading away from and below the first conveyer, a chute comprising normally fixed walls and a reciprocable bumper cooperating therewith, leading from the first to the second conveyer, and means (172) for changing the 70 position of the fixed chute with reference to the bumper.
- In witness whereof, I have hereunto subscribed my name.

ARTHUR I. RISSE.
